UNITED STATES PATENT OFFICE.

I. W. PARMENTER, OF NEW YORK, N. Y.

IMPROVEMENT IN TRUNKS.

Specification forming part of Letters Patent No. **36,021**, dated July 29, 1862.

To all whom it may concern:

Be it known that I, I. W. PARMENTER, of the city, county, and State of New York, have invented a new and Improved Trunk; and I do hereby declare that the following is a full, clear, and exact description of the same, reference being had to the accompanying drawings, making a part of this specification, in which—

Figure 1 is a transverse vertical section of my invention, taken in the line *x x*, Fig. 2; Fig. 2, a longitudinal vertical section of the same, taken in the line *y y*, Fig. 1; Fig. 3, a detached and enlarged perspective view of a hinge pertaining to the same.

Similar letters of reference indicate corresponding parts in the several figures.

This invention relates to a new and useful improvement in trunks, such as are generally used for traveling, and commonly termed "traveling-trunks."

The invention consists in providing the trunk with a series of drawers having folding bottoms, and having the case of the trunk provided with the usual lid, and also provided with a hinged removable front, all arranged in such a manner that any one of the drawers may be used separately, or all or any one of them have its bottom folded, so as to increase the capacity or enlarge the dimensions of the interior by throwing two or more drawers into one, as occasion may require, the drawers at the same time being inclosed, so as to prevent the ingress of moisture.

To enable those skilled in the art to fully understand and construct my invention I will proceed to describe it.

A represents the case or body of the trunk, of rectangular form, and provided with a lid, *B*, which is connected to the case or body by hinges *a*, as usual.

C represents the front side of the trunk, or, rather, the portion of it which extends up from the bottom *b* to a permanent strip or part, *c*, at the top. This front *C* is not permanently attached to the other parts of the case *A*, but is connected to the front edge of its bottom *b* by hinges *d*, so arranged as to admit of *C* being readily detached from the case when required. One of these hinges is shown in Fig. 3. The upper part of the front

C may be secured to the case *A* by means of a lock or any suitable fastening. A lock may also be employed for securing the lid *B* in a closed state.

D D represent drawers which slide into the case *A* at its front side. These drawers may be supported by cleats *e*, attached to the sides of the drawers and fitted in grooves *f* in the inner surfaces of the sides of the case *A*, as shown in Fig. 2. This arrangement dispenses with the use of bottom cleats between the drawers, which monopolize considerable room. When these drawers are shoved fully within the case *A*, the front *C* is allowed to close snugly against the case, so as to inclose them tightly within it, and if necessary packing or other suitable material may be attached to the edges of *C* to cause the latter to fit weather-proof against the case *A*.

Each drawer *D* is provided with a folding bottom, *E*, composed of slats *g*, connected together by hinges or by tapes *h*. These slats, when unfolded, rest upon cleats *i*, attached to the inner sides of the drawers at their lower edges, and when folded they are adjusted against either the front or back sides of the drawers, or part of them against both, as indicated in red in Fig. 1. The lower drawer, *D*, of course, does not require a folding bottom.

In the upper part of the case *A*, just above the upper drawer, *D*, there is placed a folding bottom, *F*, which is arranged precisely like those of the drawers, and when unfolded forms a compartment in the upper part of the case, access to which is had by raising the lid *B*.

When it is designed to use the drawers separately, the bottoms *E* are all unfolded, and the contents of each drawer will be kept apart, precisely the same as if each were provided with a solid or permanent bottom. Fine clothing, therefore—such as silk dresses, collars, &c., which are liable to become damaged when packed in close contact with heavier and coarser articles in a large trunk—will by this arrangement be kept in a neat state without the least injury, and when it is necessary to place larger articles in the trunk—such as band-boxes, hats, &c., or coarse clothing—the bottoms of the drawers may be folded, as well as the bottom *F*, and the whole thrown into

one compartment, or any number of the drawers may have their bottoms folded, as circumstances may require.

By having the front C of the case A removable it may be used as a writing-desk, and for convenience may be kept detached when not in traveling use.

I am aware that trunks have been provided with drawers, but not, so far as I am aware, with drawers provided with folding bottoms. I do not claim, therefore, broadly, a trunk provided with drawers irrespective of the folding bottoms of the latter; but

I do claim as new and desire to secure by Letters Patent—

A trunk composed of a series of drawers, or one or more, placed within a suitable case and provided with folding bottoms, substantially as and for the purpose specified

I. W. PARMENTER
